CORROSION INHIBITING ELECTRIC CABLE CONNECTION

René Noir, Levallois-Perret, France

Application March 14, 1949, Serial No. 81,334
In France July 2, 1948

6 Claims. (Cl. 173—259)

1

My invention relates to a device for connecting an electric cable or wire to an electric post, for instance to a post of a storage battery.

It has heretofore been customary to ensure the electric connection between a post of a storage battery and the electric cables or wires which feed the power to devices such as starter, horn, headlamp, ignition distributor, etc. by means of a cable terminal provided with an eye, which is tightened on said post.

This practice of the prior art possesses disadvantages. A wrench for tightening and loosening is necessary. Further and above all, this practice causes the post to be sulphated and consequently to be damaged after a while.

The object of my invention is the provision of a device for connecting a cable or wire to a post of a storage battery, enabling one to mount or remove the cable without using any tool and entirely preventing the post to be sulphated.

This device comprises the combination of a metallic, resiliently deformable capping member in which a post fits, of means to removably secure a cable terminal to said member, means to obtain the resilient tightening of said member on the post, and a cover, for instance, of a non-rigid material to enclose the cap and form a tight receptacle for grease or oil.

Other objects and advantages of the invention will be apparent during the course of the following description.

In the accompanying drawing forming a part of this application and in which like numerals are employed to designate like parts throughout the same,

Fig. 1 shows a first embodiment of the invention,

Fig. 2 is a cross-section of a modification,

Fig. 3 is a cross-section along III—III of Fig. 2 and

Fig. 4 is a detailed, partly cross-sectional view of the deformable capping member.

In the embodiment shown in Fig. 1, a centrally apertured member 1 whose object is to cap and tighten onto a frusto-conical post 18 of a storage battery, comprises a frusto-conical body portion 2, having longitudinal slots 4.

Externally of the top of the member 1, which is threaded, a ring 6 is screwed. This ring has a frusto-conical extension 7 causing, when the ring 6 is screwed up, the frusto-conical portion 2 of member 1 to be contracted and to be tightened on the post.

Internally of the top of member 1 an externally hollow threaded rod 9 is screwed, whose head 8

2

ensures, by means of a shim 11, the tightening of the terminal or end 10 of an electric cable 10a.

A cup 12 of rubber or elastic material is provided around the ring 6 and tightly applied on 5 the post 18 by a brim 13 designed at its lower portion.

The upper brim 12b of this cup is also tightly applied against the ring 6. Finally, the end of 10 the frusto-conical extension 7 of the ring 6 fits in a groove 16 provided at the lower portion of the cup.

This cup 12 forms a cover providing around the post 18 and connecting device a tight chamber into which it will be possible to deliver grease.

15 This grease will be distributed through channel 9a by means of an axial lubricator applied to the central bore of the head of the pressure screw 8 which clamps the terminal 10.

The above device enables a fast mounting and 20 disassembling. It is easy to understand that, for removing from the post 18 the set comprising the member 1 and the ring 6, it is enough, after having removed the shim 11 and the terminal 10, to screw home the screw 9 until the end of said 25 screw 9 is in contact with the upper end of the post 18. Upon further screwing of screw 9, the set of members 1 and 6 is caused to be raised.

As the post 18 of the storage battery is covered 30 with grease, the sulphating and oxidizing of the parts which are in contact may be reduced.

As it is shown in Figure 2 which is a cross-section of a modification, the apertured cap 13 comprises a head portion and a hollow body portion 14 having a frusto-conical internal surface and having longitudinal slots 15. The object of this cap is to be fitted and tightened on the frusto-conical end of a post 18 of a storage battery.

When the cap is arranged on the post 18, the 40 tightening is ensured by driving, on the outside of the body portion 14, a steel ring or ferrule 19, in any suitable way, for instance by means of a hammer, a press, etc.

The end 10 of the terminal of a cable 10a may 45 be arranged on the top of the cap 13, the cable 10a being thus connected to the post 18.

The cable terminal is tightened by means of 50 a screw or threaded rod 16, the head 16a of which may be set in a disc 17 of synthetic material. This screw or threaded rod 16 is screwed in the cap 13.

A cup 20 of rubber or synthetic material and having a bottom aperture is provided around the connecting device. The brim 20a of this cup fits in a groove 17a of the disc 17, and a side

aperture 20c is provided for the passage of the end 10 of the cable terminal 10a. The grease covering the end of the post is contained in the cup 20.

For removing the connecting device from the post, the cable terminal is previously removed, then the threaded rod 16 is screwed home in such a manner that it exerts a pressure on the end of the post 18, which causes, by a further screwing up, the cap 13 to raise.

What I claim is:

1. A device for the connection of an electric conductor to an electric post, comprising in combination a cup having a bottom aperture adapted to fit tightly on said post, said post projecting within said cup through said aperture, said cup providing, round said post, a chamber for receiving a protecting agent, means for electrically connecting said conductor to said post while providing a cover for said cup, said means comprising a cap adapted to fit on said post within said cup and provided with a threaded aperture in its top part, means for tightening the walls of said cap against said post and means for clamping said electric conductor on said cap, said last means engaging said threaded aperture.

2. The device of claim 1, said last means comprising a screw having a threaded stem engaging in said threaded aperture.

3. The device of claim 2, said stem of said screw having an axial length considerably greater than the thickness of said head portion of the cap, for the purpose set forth.

4. The device of claim 1, said last means comprising a headed screw engaging in said threaded aperture, said device including an insulating cover gripping said screw head and having an annular groove in its lower face for engaging the upper edge of said cup.

5. The device of claim 1, said cup having a lateral opening for the passage of said conductor.

6. The device of claim 1, further comprising a constraining ring on said cap, arranged for 15 sliding, axial movement along the same.

RENÉ NOIR.
